CHANGE MOTION MECHANISM FOR JACQUARD LOOMS

Floyd C. Matthews, Fairlawn, N. J.

Application February 28, 1936, Serial No. 66,206

9 Claims. (Cl. 139—175)

This invention relates, generally, to Jacquard looms, and the invention has reference, more particularly, to a novel change motion mechanism for Jacquard looms.

5 In Jacquard looms employing shuttle carrying frames or battens having a plurality of superimposed shuttles for carrying weft bobbins having threads of differing colors, such as the well known Fletcher type of Jacquard label loom
 10 made by the Fletcher Works of Philadelphia, and disclosed in Patent 786,237, dated Mar. 28, 1905, to Schaum, it is necessary to raise and lower the shuttle carrying frame or batten to accommodate the superimposed shuttles carrying
 15 the various colors to the shed of the warp and heretofore an extremely complicated mechanism known as the Fletcher change motion has generally been used for this purpose. Not only does this complicated mechanism get out of order frequently in use, but the same is apt to allow the shuttle carrying frame or batten to remain in
 20 its lowered position on the lay, in which position there is no take-up on the knee roll due to the fact that the design color or filling thread and not the ground color or base thread is being woven, since the ground color is carried by the lower shuttle or line of shuttles that are below the shed when the batten is in its lowered position, and since the take up mechanism controlled by the jacquard mechanism does not operate the knee roll when the filling thread is being woven, so that in time this filling thread
 25 piles up to such an extent as to cause the shuttles to jerk the warp threads, resulting in the weaving out of the warp as is well known to those skilled in the art, thereby necessitating lengthy and expensive repairs.

The principal object of the present invention is to provide a novel change motion mechanism for Jacquard looms that is of extremely simple and rugged construction, the same providing for the raising and lowering of the shuttle carrying frame or batten as desired, the shuttle carrying frame or batten moving up and down along guides provided on the lay or lay batten, and being so constructed and arranged as to provide for the positive raising of the shuttle carrying frame or batten and the holding of the same in raised position at the end of each weaving operation, thereby insuring the weaving of the ground or base color or thread and preventing the destruction or weaving out of the warp threads.

Another object of the present invention lies in the provision of a novel change motion mechanism of the above character having wheel-crank

operated relatively movable slides, one of said slides carrying cam means for raising and lowering the shuttle carrying frame or batten, the interconnection of said slides being such that the raising of the shuttle carrying frame or batten is positive and is dependent merely upon the operation of the wheel-crank, whereas the lowering of the shuttle carrying frame or batten is dependent upon the jacquard mechanism.

Other objects and advantages of this invention, not at this time more particularly enumerated, will be clearly understood from the following detailed description of the same.

The invention is clearly illustrated in the accompanying drawings, in which:

Fig. 1 is a fragmentary view in end elevation of a Jacquard loom illustrating the application of the novel change motion mechanism of the invention thereto, the control parts of the mechanism being positioned for effecting vertical reciprocation of the batten.

Fig. 2 is an enlarged perspective view of a portion of the change motion mechanism of Fig. 1.

Fig. 3 is a view similar to Fig. 1 but shows the control parts of the mechanism positioned for retaining the batten in raised position, and

Fig. 4 is an enlarged perspective view of a portion of the structure of Fig. 3.

Similar characters of reference are employed in the above views to indicate corresponding parts.

Referring now to the said drawings, the reference numeral 1 designates the frame of a Jacquard loom having a shuttle carrying frame or batten 2 arranged for vertical reciprocation upon the lay or lay batten (not shown) by the novel change motion mechanism of this invention. Old and well known parts of the loom construction have been omitted for the sake of clearness in the drawings.

The loom motor 3 drives a gear 4 fixed on a shaft 5 having a bevel gear 6 fixed thereon which latter gear meshes with a similar bevel gear 7 fixed on a vertical drive shaft 8, whereby the drive shaft 8 is driven from motor 3. A bevel gear 9 is fixed on drive shaft 8 and drives a bevel gear 10 having a spur gear 11 secured thereto, which latter gear meshes with a toothed wheel-crank 12 for rotating the latter. Wheel-crank 12 carries a crank pin 14 to which is pivotally connected one end of a connecting rod 15, the other end of which is pivotally connected to a stud 16 projecting from a driving slide or member 17 that is longitudinally movable within a guide box 18 that is fixed upon a back plate 19.

carried by the frame 1 of the loom. The guide box 18 is shown as having a longitudinal slot or opening 20 in its front wall to accommodate the projecting stud 16 of slide 17 and connecting rod 15. The slide 17 is illustrated as having a forward rectangular projecting portion 21 movable within the slot 20.

A driven member or slide 22 of substantially the same dimensions as the driving slide 17 is also longitudinally movable within the guide box 18, the same being adapted to be driven from the driving slide 17. Driven slide 22 has a lift cam 25 secured to the top surface of the same as by dowel pins 26. Lift cam 25 has an inclined camming surface 27 extending upwardly from the top surface of the driven or rear slide 22 and terminating in a flat horizontal top surface 28 for actuating a roller 29 on lever 30. Roller 29 is shown carried by one end of lever 30 which latter is pivoted as at 31 upon the loom frame and has its other end connected to a cable 32 leading over sheaves 33 for supporting the batten 2. When roller 29 engages the top surface of driven or rear slide 22 as shown in dot-dash lines in Fig. 1, the batten 2 is in its lower position, whereas when roller 29 engages the flat top surface of the lift cam 25 as shown in full lines in Fig. 1 the batten is in its upper position.

In order to effect movement of the driven slide 22 toward the right in the figures, corresponding to the movement of roller 29 up the inclined camming surface 27 and the raising of the batten, the driven slide is provided with a forwardly projecting stud or pin 23 that is adapted to enter a slot 24 provided in the right end portion of the driving slide 17, so that when the driving slide overtakes the driven slide while moving toward the right the slot 24 engaging pin 23 also serves to positively drive slide 22 to the right to elevate the batten.

In order to move the driven slide toward the left in the figures, a latch 34 has one end thereof pivoted upon a stud 36 projecting from the side of lift cam 25, the other end of this latch being arranged to engage against a projection or stop 37 provided on the top of driving slide 17. Latch 34 has an operating pin 38 projecting therefrom to be engaged by a lifting lever 39 pivoted at one end at 40 on the guide box 18 and having its other end connected to the lower end of an upwardly extending link 41 that has its upper end connected to a lever 42.

Lever 42 is pivoted at 43 upon the machine frame and is arranged to rest upon a plate cam 44 turnable upon a fixed shaft 45. Plate cam 44 has alternate high and low points and is turned by a pawl 45' and a cooperating ratchet wheel 46 fixed on the plate cam 44. Pawl 45' is carried by a lever 47 that is actuated by a cable 48 passing over pulley 51 and connected to pairs of cords 49 and 50 connected to the lifting hooks of the jacquard mechanism. Each time one of the pairs of cords 49 or 50 pulls upon the cable 48 the pawl 45' is given a stroke to effect movement of cam plate 44, whereby the lever 42 is alternately raised and lowered. Each time lever 42 is raised, it acts through link 41 to raise lifting lever 39 and effect the raising of latch 34 so that the latter is raised from the path of movement of projection 37, whereby the drive from the driving slide to the driven slide for lowering the batten is disconnected. When lever 42 is lowered the latch 34 is lowered to be engaged by the projection 37.

In use, let it be assumed that the motor 3 is

running and that the cards of the jacquard mechanism are about to start their cycle of movement for producing a desired pattern in the cloth as it is woven. Before the starting of the cycle, the plate cam 44 is in the position shown in Fig. 3, i. e. with a high point thereof elevating the lever 42, whereby the latch 34 is held raised so that although driving slide 17 is being reciprocated by connecting rod 15, the driven slide 22 is stationary and in the position shown in Fig. 4, previous coaction of slot 24 with stud 23 having caused the driven slide to be moved to the right limit of its travel in the slide box, whereby the roller 29 was caused to roll up the camming surface 27 of lift cam 25 to remain upon the top surface 28 of this cam so that the batten is held in raised position as is desired in which position the ground or base color is being woven, thereby preventing injury to the warp.

Just as the cards start their cycle, the proper pair of cords 49 or 50, as the case may be, are pulled by the jacquard mechanism, thereby actuating plate cam 44 so that a low point thereof moves under lever 42 as illustrated in Fig. 1, whereby latch 34 is lowered into the path of movement of projection 37 (see Fig. 2) resulting in slide 17 acting through this latch to drive the driven slide 22 toward the left into the dot-dash position of Fig. 1, the roller 29 thereby being caused to roll down the camming surface 27 of the lift cam and effecting the lowering of the batten and the weaving of a filling color or thread, i. e. the color giving the desired design to the fabric. Continued reciprocation of the driving slide causes similar movement of the driven slide, the latter being driven toward the right by the coaction of slot 24 and pin 23 and toward the left by the action of latch 34, thereby alternately raising and lowering the batten to accommodate the movements of the superimposed shuttles to the shed of the warp.

When the cards have run their cycle, the proper pair of cords 49 or 50 are pulled by the jacquard mechanism, thereby turning cam plate 44 so that a high point moves under lever 42, thereby raising latch 34 and stopping the alternate raising and lowering of the batten 2, the latter being left, however, in raised position as is desired owing to the coaction of slot 24 with pin 23 to move the driven slide 22 to its right hand limit of travel before stopping the movement of this slide, in which position the lower shuttle or line of shuttles carrying the ground color are actuated to weave the body of the fabric.

In practice, the stroke of the wheel-crank is of such length that the period of dwell of the follower roller 29 upon the flat top of the driven slide 22 and upon the flat portion 28 of the lift cam is such that the period of rest of the batten is longer than the periods of rise or lowering thereof, thereby giving the shuttles ample time to perform their function without any possibility of injuring the warp.

The novel change motion mechanism of this invention is especially valuable when running looms at high speed since the gearing ratio for driving the slides is such that these slides make but one half as many reciprocations as the number of picks per minute of the machine resulting in smooth and quiet operation at high loom speed.

As many changes could be made in the above construction and many apparently widely differ-

ent embodiments of this invention could be made without departing from the scope thereof, it is intended that all matter contained in the above description or shown in the accompanying drawings shall be interpreted as illustrative and not in a limiting sense.

Having now described the invention, what I claim and desire to secure by Letters Patent is:

1. In a Jacquard loom having a vertically reciprocable batten, change motion mechanism for causing the reciprocation of said batten, said mechanism comprising a continuously reciprocating slide member, a second slide member, a positive drive connection between said members for moving said second slide member in one direction from said first slide member, a disconnectable driving connection between said slide members for moving said second slide member from said first slide member in the reverse direction, and motion transmitting means actuated by said second slide member for effecting the reciprocating movement of said batten.

2. Change motion mechanism as in claim 1 and in which said disconnectable driving connection comprises latch means so constructed and arranged that when said disconnectable drive between said slide members is broken, the batten will be returned to raised position by said positive drive connection, thereby eliminating the weaving out of the warp.

3. In a Jacquard loom having jacquard mechanism and a vertically reciprocable batten, change motion mechanism for causing the reciprocation of said batten, said mechanism comprising, a continuously reciprocating driving slide member, a driven slide member, abutment means for interconnecting said slide members for effecting a positive drive of said driven slide member in the direction causing the raising of the batten, and separate latch means for disconnectably interconnecting said slide members to effect the drive of said driven slide member in the direction to lower the batten, said separate means being controlled from said jacquard mechanism.

4. In a Jacquard loom having jacquard mechanism and a vertically reciprocable batten, change motion mechanism for causing the reciprocation of said batten, said mechanism comprising, a continuously reciprocating driving member, a driven member, cooperating slot and pin means for interconnecting said members for effecting a positive drive of said driven member in the direction causing the raising of the batten, and separable latch and cooperating stop means for interconnecting said members to effect the drive of said driven member in the direction to lower the batten, said separable latch and stop means being controlled from said jacquard mechanism, whereby said latch and stop means is disconnected upon the completion of an operation of the jacquard mechanism, thereby cutting off the drive for lowering the batten.

5. In a Jacquard loom, a jacquard mechanism and a vertically reciprocable batten, change motion mechanism for causing the reciprocation of said batten, said mechanism comprising, a continuously reciprocating driving member, means for reciprocating said driving member, a driven member having a projection arranged to

be engaged by said driving member for moving the driven member in a direction to effect the raising of the batten, said driven member having a pivoted projection arranged to be engaged by said driving member for moving the driven member in a direction to effect the lowering of the batten, and means operated from said jacquard mechanism for turning said pivoted projection out of engagement with said driving member, whereby lowering movements of the batten cease.

6. In a Jacquard loom having jacquard mechanism and a vertically reciprocable batten, change motion mechanism for causing the reciprocation of said batten, said mechanism comprising, a continuously reciprocating driving member, means for reciprocating said driving member, a driven member having a pin projection fixed thereon and arranged to be engaged by said driving member for moving the driven member in a direction to effect the raising of the batten, said driven member having a pivoted latch projection arranged to be engaged by said driving member for moving the driven member in a direction to effect the lowering of the batten, and pawl and ratchet means operated from said jacquard mechanism for turning said pivoted latch projection out of engagement with said driving member, whereby lowering movements of the batten cease so that the same is held in raised position.

7. In a Jacquard loom in combination, a jacquard mechanism, a vertically reciprocable batten, and change motion mechanism for reciprocating said batten, said mechanism comprising a reciprocable member, cam means provided on said member, a follower cooperating with said cam means, transmission means connecting said follower to said batten, a positive drive connection for driving said reciprocable member in a direction to cause said cam means to effect the raising of said batten, and a disconnectable drive connection controlled from said jacquard mechanism for driving said reciprocable member in the reverse direction to cause said cam means to effect the lowering of said batten.

8. In a Jacquard loom in combination, a jacquard mechanism, a vertically reciprocable batten, and change motion mechanism for reciprocating said batten, said mechanism comprising a reciprocable member, a lift cam provided on said member, a lever having a follower roller cooperating with said lift cam, said lever being connected to said batten for actuating the latter, driving means, a positive drive connection from said driving means for driving said reciprocable member in a direction to cause said lift cam to raise said follower roller and effect the raising of said batten, and a disconnectable drive connection from said driving means and controlled from said jacquard mechanism for causing said lift cam to lower said follower roller and effect the lowering of said batten.

9. In a Jacquard loom, a vertically reciprocable batten, a horizontally reciprocable lift cam, a follower cooperating with said lift cam and connected to said batten for raising and lowering the same, and horizontal surface portions provided at the ends of said cam providing periods of rest of said follower and hence of said batten that are longer than the periods of motion of the same.
